UNITED STATES PATENT OFFICE.

ROBERT S. POLLARD, OF PITTSBURG, PENNSYLVANIA.

DEVICE FOR OPERATING BLAST-FURNACE SNORT-VALVES.

SPECIFICATION forming part of Letters Patent No. 694,988, dated March 11, 1902.

Application filed May 10, 1901. Serial No. 59,647. (No model.)

To all whom it may concern:

Be it known that I, ROBERT S. POLLARD, a citizen of the United States of America, residing at Pittsburg, in the county of Allegheny and State of Pennsylvania, have invented 5 certain new and useful Improvements in Valve-Operating Devices for Snort-Valves as Applied to Blast-Furnaces, of which the following is a specification, reference being had 10 to therein to the accompanying drawings.

This invention relates to certain new and useful improvements in mechanism for operating snort-valves or relief-valves employed in connection with blast-furnaces. It is a 15 well-known fact that heretofore valves of this class have been extremely difficult to operate at times. Furthermore, by the present system of operation it often occurs that the valves stick and are rendered inoperative for 20 a time, which is apt to cause a great loss of material in and around the furnace and requiring considerable time and expense to place the parts in an operative position.

It is therefore the object of this invention 25 to overcome these difficulties and to construct a device of the above-described character that will be extremely simple, strong, durable, and comparatively inexpensive to manufacture; furthermore, one that can be easily 30 operated and not liable to become out of order or stick.

With the above and other objects in view the invention consists in the novel combination and arrangement of parts to be herein- 35 after more fully described, and specifically pointed out in the claim.

In describing the invention in detail reference is had to the accompanying drawings, forming a part of this specification, and 40 wherein like numerals of reference indicate corresponding parts throughout the several views, in which—

Figure 1 is a front view of my improved snort-valve, showing the operating mechanism therefor. Fig. 2 is a side view of the 45 same, showing in dotted lines the relative position of the parts as the valve is operated. Fig. 3 is an enlarged end view of the main valve. Fig. 4 is a vertical sectional view of 50 the auxiliary valve. Fig. 5 is a plan view showing the furnace broken away and in sec-

tion and showing my improved device connected to the cold-blast pipe.

In the drawings the reference-numeral 1 indicates a casing which is usually cylindrical 55 in form, having arranged therein a valve 2, said valve being centrally pivoted at 3 upon a shaft 4, said shaft extending through the casing 1, having secured thereon a toothed wheel 5.

The reference-numeral 6 indicates an operating-lever secured to the ends of the shaft 4 in close proximity to the toothed wheel 5. This lever may be operated in any suitable 60 manner.

The reference-numeral 7 represents a casing arranged on the casing 1, in which is arranged an auxiliary valve 8, said auxiliary valve being likewise centrally pivoted to a shaft 9, extending through the casing 7, carrying a toothed wheel 10, said toothed wheel corresponding with the toothed wheel 5. A bracket 11 is rigidly secured to the casing 7, giving additional strength and providing a suitable bearing 12 for the shaft 9, upon which 75 the toothed wheel 10 is mounted.

The reference-numeral 14 represents an endless chain connecting the wheels 5 and 10, which is operated by means of the lever 6, thereby rotating the wheels 5 and 10 in unison for the purpose to be hereinafter explained.

In operation the current of air enters the casing through the port, as indicated by arrows, whence, should the main valve be closed, 85 it will be deflected upward toward the arrow shown in dotted lines and allowed to exhaust through the auxiliary valve. Should the main valve be open, however, the air will of course be permitted to enter the furnace.

It will be noted that when the main valve is closed, as shown in dotted lines in Fig. 2 of the drawings, the auxiliary valve will be opened, as shown in Fig. 4, thereby closing the blast and opening the auxiliary valve, allowing the air to exhaust by way of the auxiliary valve. It will further be noted that the valve 2 when closed assumes an oblique position and acts as a deflecting-plate, deflecting the air and conveying the same into its proper course or channel. It will further be observed that the valves 2 and 8 operate in uni-

son and that when one is partly open the other will be partly closed in order to regulate the blast when desired.

In the common practice the air is carried from blowing-engines (not shown) through the cold-blast main 15 to stoves 16 and is then conveyed through the stoves in order that it may be heated before reaching furnace 17. It is then carried from stove 16 through a hot-blast main 19 to a circular pipe around a furnace commonly called a "bustle-pipe" 18 and is admitted from this pipe to the furnace through blow-pipe and twyers. The pipe marked 20 is simply a by-pass which can be used if the stoves are heating the air too hot, in which case cold air can be admitted through this by-pass to commingle with and temper hot air in the hot-blast main. Of course I do not claim the above as part of my invention at all, but have simply shown and described the same in order to show the application of the snort-valve as applied to a blast-furnace.

The many advantages obtained by the use of my improved valve will be readily appar-

ent from the foregoing description, taken in connection with the accompanying drawings.

It will be noted that various changes may be made in the details of construction without departing from the general spirit of my invention as claimed.

Having fully described my invention, what I claim as new, and desire to secure by Letters Patent, is—

In combination with a furnace, a main casing, an auxiliary casing mounted thereon, 35 ports in said casings, a port for establishing communication between the said casings, shafts secured in said casings, valves mounted on said shafts, a sprocket-wheel mounted on each shaft, a chain connecting the said 40 wheels, and a lever connected to one shaft, substantially as described.

In testimony whereof I affix my signature in the presence of two witnesses.

ROBERT S. POLLARD.
